UNITED STATES PATENT OFFICE

128,151

DESIGN FOR A MAGNETOELECTRIC GENERATOR

Edward A. Vogel, Beloit, Wis., assignor to Fairbanks, Morse & Co., Chicago, Ill., a corporation of Illinois

Application October 31, 1940, Serial No. 96,227

Term of patent 3½ years

To all whom it may concern:

Be it known that I, Edward A. Vogel, a citizen of the United States, residing in the city of Beloit, county of Rock, and State of Wisconsin, have invented a new, original, and ornamental Design for a Magnetolectric Generator, of which the following is a specification, reference being had to the accompanying drawing, forming a part thereof.

In the drawing:

Fig. 1 is a top plan view of the magnetolectric generator, showing my new design; Fig. 2 is a longitudinal side elevational view thereof; Fig. 3 is a bottom plan of the magneto; Fig. 4 is an end elevational view at the impulse coupling end of the magneto, and Fig. 5 is an end elevational view of the opposite or distributor end of the magneto. The side elevation of the magneto opposite that shown by Fig. 2, corresponds in all important respects, to the view of Fig. 2.

I claim:

The ornamental design for a magnetolectric generator, substantially as shown and described.

EDWARD A. VOGEL.
